INVENTOR.

UNITED STATES PATENT OFFICE.

JOVAN I. BOZOWICH, OF SAN FRANCISCO, CALIFORNIA.

STREET AND STOP INDICATOR FOR RAILWAY-CARS.

1,175,334.

Specification of Letters Patent.

Patented Mar. 14, 1916.

Application filed November 14, 1914. Serial No. 872,253.

To all whom it may concern:

Be it known that I, JOVAN I. BOZOWICH, a citizen of the United States, residing in the city and county of San Francisco, State of California, (whose post-office address is 2411 Woolsey street,) have invented new and useful Improvements in Street and Stop Indicators for Railway-Cars, of which the following is a specification.

10 This invention relates more particularly to indicators, to be placed within street cars and operated from an outside source, to indicate to the passengers the name of the next street or stop.

15 Among the objects of this invention are to provide an automatically operated indicator, simple in construction easily installed and reliable in operation; in which the chronological tape may be easily removed and substituted, when the car is shifted from one division to another in which the intersecting street names will be different.

20 Other objects and advantages will appear as the description progresses in connection 25 with the one sheet of drawing forming a part of this specification to which like reference characters have been applied.

25 In the drawings: Figure 1 is a side elevation of a street car partially broken away 30 in cross section, to disclose the installation of this invention therein. Fig. 2 is an end elevation of the same in cross section taken on the line II-II Fig. 1. Fig. 3 is a detail diagrammatic plan view of the inclosing casing shown in cross section disclosing the interior mechanisms. Fig. 4 is a similar view in side elevation of the stop and chronological strip release mechanism. Fig. 5 is a detail plan view of the pivoted 35 trigger mechanism. Fig. 6 is a detail in side elevation of the manual control of the release mechanism. Fig. 7 is a front elevation in detail of the take up reel. Fig. 8 is a plan view from above of the same in cross 40 section taken on the line VIII-VIII Fig. 7.

45 In detail the construction illustrated in the drawing, includes the car-body 1, mounted upon suitable trucks 2 running upon the rails 3. The indicator comprises an inclosing casing 4, mounted in the end of the car, within convenient sight of the passengers. The front of the casing is glazed as at 5 to expose the chronological strip therethrough. This strip is wound upon the reel 6, and 50 passes over the idlers 7 and 8 and engages the spring take up reel 9. The reels 6 and

9 are mounted upon the shafts 10 and 11 journaled in the casing 4. The chronological strip 12 is provided with the notches 13 in the edge thereof. The strip 12 is controlled by the pawl 14, having the heads 15-15 engaging the notches 13 therein. The strip 12 runs behind the guide 16, fixed to the pawl and overlying the push-rod. The pawl 14 is mounted on the end of the push 60 rod 17, that is guided in the casing 4 at the top, and passes through the floor 18 at the bottom. The rod 17 has the collar 19 fixed thereon to engage the adjustable stop 20, to regulate the drop of the pawl 14. A 65 thrust collar 21 is fixed on the shaft 17 beneath the floor, and is engaged by the yoke 22 on the end of the lever 23, pivoted at 24 on the bracket 25, fixed to the underside of the car floor. This lever is provided with a 70 downwardly extending trigger 26, adapted to engage the trip 27 attached to the rail 3, at the various points along the right of way where it is desired that the indicator should be released, to designate the name of the intersecting points being approached. The trigger is restored to its normal vertical position by the tension of the spring 28, attached to the underside of the car floor and to the extension 29, on the opposite side of 75 the pivot 24 from the lever 23.

80 The indicator is operated substantially as follows: The tension of the spring 30 confined within the reel 9 is wound up by the conductor, who places a key upon the 85 squared end 31 of the shaft 10; the tension of the spring being wound up as the strip 12 is wound onto the reel 6, the pawl being elevated as the notches 13 pass thereunder. With the chronological strip in starting position, the car progresses until the trigger 90 26 passes over the first trip 27; this forces the trigger backward, elevates the yoke 22, pushes up the rod 17 releasing the pawl 14 from the strip 12; the instant that the pawl 95 14 was released from the strip, the trigger has passed entirely over the trip 27 and been restored to the normal position by the tension of the spring 28, permitting the pawl 14 to drop in time to engage the next set of 100 notches 13, that will stop the chronological strip, exposing the designation of the next succeeding intersecting street; this operation being repeated each time the trigger engages a properly placed trip on the right of 105 way. Should a trip be missing or the trip fail to properly release the strip, a manual 110

- control is provided whereby the conductor at the opposite end of the car may release the pawl as often as necessary, to permit the strip to progress so as to indicate correctly.
- 5 This manual control consists of the handle 32 on the cord 33, passing over the pulley 34 and attached to the bell crank lever 35 pivoted at 36, adjacent to the rod 17, the opposite end of the lever being pivoted at 37 to 10 the pawl; whereby a pull on the handle 32 elevates the pawl 14.

It is obvious that the mechanism described may be duplicated at opposite ends of the car, if the car is designed to operate in either 15 direction, or the indicator may be so constructed that the reels 6 and 9 may be removed from the mechanism at one end of the car and transferred to the other, to save the necessity of having two chronological 20 strips, one of which would remain inactive. The construction of the trigger is such that if properly mounted on opposite ends of the car, only one of the triggers would operate the release mechanism going in one direction.

I have disclosed this invention in its simplest form, but I do not wish to be limited to the particular mechanism shown and described herein as many variations may be 30 made within the spirit of this invention.

I claim:

1. A car indicator comprising a receptacle, a carrying spool rotatably mounted in said receptacle, a winding spool rotatably mounted in said receptacle, a ribbon wound upon said carrying spool and connected with said winding spool, said ribbon having one edge portion provided with notches, a rod slidably mounted and provided with an arm extending along said ribbon and provided with teeth for fitting into the notches thereof to releasably hold said ribbon in a set position, and means for raising said rod to move said teeth out of engagement with 45 said ribbon.
2. A car indicator comprising a receptacle, a ribbon movably mounted in said receptacle and provided with notches leading

from one edge, a slidably mounted rod, a pin carried by said rod and extending along 50 said ribbon upon the opposite side thereof from said rod, a latch arm extending from said rod and provided with teeth for fitting into the notches of said ribbon, and means for moving said rod to a position to release 55 said ribbon from said teeth.

3. A car indicator comprising a receptacle, a slidably mounted rod having a head at its upper end, a finger extending from the head of said rod, a latch arm extending 60 from the head of said rod, an indicating ribbon movably mounted in said receptacle and extending between said rod and finger and extending substantially parallel to said latch arm whereby said latch arm may engage said ribbon to releasably hold the ribbon in a set position, and means for moving said rod to release said ribbon from said latch arm.

4. A car indicator comprising a receptacle, a ribbon movably mounted in said receptacle, a slidably mounted rod extending into said receptacle, means carried by said rod for engaging said ribbon to releasably hold the ribbon in a set position, 75 a pivotally mounted lever provided with a forked end through which said rod passes, an abutment collar carried by said rod for engagement by the forked end of said lever, and a trigger arm extending from said lever, movement of said lever in one direction moving said rod to release said ribbon.

5. An indicator comprising a receptacle, a ribbon movably mounted in said receptacle and provided with notches leading 85 from one edge, a latch provided with teeth for fitting into the notches of said ribbon to releasably hold said ribbon in a set position, and means for moving said latch to a position to release said ribbon from said 90 teeth.

JOVAN I. BOZOWICH.
